PUMP HEAD

Raymond E. Swanson, Lawrenceburg, Ind., assignor to A. D. Cook, Inc., Lawrenceburg, Ind., a corporation of Indiana

Application May 10, 1933, Serial No. 670,287

8 Claims. (Cl. 74—50)

My invention is concerned with pump heads for deep well pumps. Among the objects of my invention are to produce a compact pump head which will be of simple and economical construction and which, at the same time, will have ample strength and durability. A further object of my invention is to provide for the adequate lubrication of all working parts of the pump-head. Still another object of my invention is to so construct the pump head that the pump rod and drop pipe can be easily removed. Another object of my invention is to so construct a pump-head that all working parts will be readily accessible.

In carrying out my invention I provide for the pump head an enclosing casing within which is slidably mounted for vertical reciprocation a cross-head to which the upper end of the pump rod is to be connected. This cross-head is reciprocated through Scotch-yoke mechanism including a gear meshing with a pinion on a drive shaft, the gear, pinion, and drive-shaft being mounted for removal from the casing as a unit. The casing, in its bottom portion, contains a supply of lubricant into which the cross-head, at the bottom of its stroke, and the gear dip. The pinion by which the gear is driven is located above the oil level in the casing; and the parts are so arranged that the oil expelled from the point at which the gear and pinion mesh is so directed as to lubricate those parts of the device which would not otherwise receive sufficient oil.

The accompanying drawings illustrate my invention: Fig. 1 is a vertical section through the pump-head on the line 1—1 of Fig. 2; Figs. 2 and 3 are vertical sections on the lines 2—2 and 3—3 respectively of Fig. 1; Fig. 4 is a fragmental vertical section on the line 4—4 of Fig. 1; Fig. 5 is a perspective view of the complete pump-head; Fig. 6 is a rear end elevation of the head; Fig. 7 is a perspective view of the driving mechanism of the head removed from the casing; Fig. 8 is a perspective view of the casing, with the driving mechanism and cross-head removed; Fig. 9 is a perspective view of the cross-head and its associated guide-rods removed from the casing; and Fig. 10 is a fragmental section on the line 10—10 of Fig. 2.

The casing in which the working parts of the head are enclosed is of a general parallelepipedal shape and has a bottom 12, front and rear walls 13 and 14, side walls 15, and a top wall 16. In the upper rear portion of the casing, the rear wall 14, side walls 15, and top wall 16 are cut away to provide an opening for the insertion of the working parts. On the outer side of the front wall near the bottom there are provided forwardly extend-

ing brackets 17 on which the discharge 18 is mounted. The drop pipe 19 extends downwardly from the discharge 18 into the well and receives the pump-rod 20 which extends upwardly beyond the discharge 18 through a stuffing box 21 therein.

For the purpose of reciprocating the pump-rod 20, it is rigidly connected to a cross-head 25 mounted on vertically extending guide rods 26 within the casing. At its upper and lower front corners, the casing is provided interiorly with bosses 27 which are drilled and reamed to receive the guide rods 26 in parallel relation. The guide rods are secured in place by means of set screws 28 in the upper bosses. Plugs 29 close the lower ends of the holes in the lower bosses 27 and prevent any possibility of oil-escape.

The cross-head 25 is reciprocated by Scotch-yoke mechanism driven from a drive shaft 31 rotatably supported in a bracket 32 mounted within the casing. For the purpose of supporting the bracket 32, the side walls 15 of the casing are provided interiorly with shelves 33 upon which the bracket 32 rests and which receive screws 34 by means of which the bracket may be held in place.

On the inner end of the drive shaft 31 there is provided a pinion 36 which meshes with a gear 37 secured to the forward end of a second shaft 38 which is received in suitable bearings in the lower part of the bracket 32.

At an eccentric point on the front face of the gear 37 there is rotatably mounted, as by means of a shouldered bolt 40, a block 41 having upper and lower parallel faces and adapted to be slidably received between horizontal flanges 42 on the rear face of the cross-head 25. The upper one of the flanges 42 is strengthened and braced by means of ribs 43, preferably cast integrally with the cross-head.

In the preferred method of securing the pump-rod 20 to the cross-head 25, the upper end of the pump rod is shouldered and extends through a lug 45 removably secured to the front face of the cross-head 25 and extending through a vertical slot in the front wall of the casing. Conveniently, the lug 45 has at its rear end a cylindrical shank 46 which extends into a hole in the cross-head 25 and which is drilled at its end and tapped for the reception of a screw 47 by which the lug 45 is held in place. The upper end of the pump-rod 20 is threaded for the reception of a nut 48 which, in co-operation with the shoulder on the pump-rod, secures the pump rod to the lug 45.

In cases where the pump-head is to be used in conjunction with an air-cushioned tank into

which the liquid raised by the pump discharges, the pump-head may include an air-pump 50 mounted on the discharge T 18 and having a piston rod 51 connected to the lug 45 by means of an extension 52 secured beneath the nut 48.

For the purpose of driving the pump-head, I prefer to use an electric motor 55 mounted on a bracket 56 at the side of the casing. Preferably, each of the side walls 15 of the casing is provided 10 with a set of outwardly extending threaded bosses 57 by means of which the bracket 56 can be mounted on either side of the casing, as illustrated in Fig. 6.

The motor 55, mounted on either side of the 15 casing, may be connected by a belt 58 with a pulley 59 on the outer end of the drive shaft 31.

I contemplate that when the pump-head is in operation the lower portion of the casing will contain a supply of oil into which the cross-head 25, 20 at the bottom of its stroke, and the gear 37 will dip. The bottom of the cross-head may be formed with inclined side walls as shown in Figs. 1 and 9 to reduce splash. A gage 61 may be provided on the side of the casing to indicate the oil-level therein. As the gear 37 rotates, oil adheres 25 to its teeth and is expelled axially at the point where the gear 37 meshes with the pinion 36. The oil expelled forwardly is projected against the rear face of the cross-head 25 and runs downwardly thereon under the influence of gravity to lubricate the upper face of the block 41. The oil expelled rearwardly from the point at which the pinion 36 and gear 37 mesh is received in a 30 properly positioned groove 62 in the bearing which rotatably supports the shaft 31.

Conveniently, the shaft 31 is mounted in two 35 axially spaced bearings in the bracket 32 and between these two bearings there is provided an oil well 63 into which the groove 62 discharges. A second groove 62' located in the rear bearing for the shaft 31 receives oil from the well 63 and thus provides for the lubrication of that bearing. Excess oil supplied to the reservoir 63 and to the 40 bearings for the shaft 31 flows down the walls of the bracket 32 and lubricates the bearings for the shaft 38, which bearings may be provided with oil grooves 64.

A cover 66 is provided for the casing. In its 45 upper wall, this cover may have a large opening closed by a closure 67 which is held in place by a thumb nut 68 on the end of a rod 69 that projects upwardly and rearwardly from the bracket 32 through the opening in the cover 66. The thumb-nut 68 serves to hold both the closure 67 and the cover 66 in place, and the thumb nut and closure may be removed at any time for the purpose of inspection or to permit additional lubricant to be supplied to the casing.

A shield 70, conveniently of sheet-metal, is 50 mounted on the front of the casing and encloses the upper end of the pump-rod 20 and of the air-pump 50.

Among the advantages of the pump-head described is compactness, especially in respect to 55 height. The possibility of mounting the driving motor on either side of the casing increases the flexibility of installation. Adequate lubrication for all working parts is insured. Removal from the casing of any or all working parts is quickly 60 and easily effected. The gear 37 can be driven in either direction, and by reversing its direction wear is distributed and working life materially increased. The pump rod and drop pipe can be pulled after removing the shield 70 and the lug 45 without distributing any other parts of the head.

The whole construction is simple, sturdy, and economical to manufacture.

I claim as my invention:

1. A pump head, comprising a casing, a cross-head mounted for sliding movement in said casing, a bracket mounted within said casing, a rotating element mounted on said bracket for rotation on an axis perpendicular to the path of movement of said cross-head, a block rotatably mounted at an eccentric point on said rotatable element, a transverse guide-way on said cross-head for slidingly receiving said block, and a drive shaft rotatably supported in said bracket and operatively connected to said rotatable element, said bracket, drive shaft, and rotating element being removable as a unit from the casing and from association with said cross-head. 15

2. A pump head, comprising a casing, a cross-head mounted for sliding movement in said casing, means for reciprocating said cross-head, a 20 pump-rod, a lug and means for detachably securing said lug to said cross-head, said casing being provided in one wall with a slot through which said lug projects and said pump-rod being connected to that portion of said lug which projects beyond the slotted casing-wall. 25

3. A pump-head, comprising a casing, a reciprocal member, means located within said casing for reciprocating said reciprocal member, said means including a shaft projecting from said casing, a motor for driving said shaft, and two sets of motor-mounting means located exteriorly of said casing and on opposite sides thereof, whereby said motor may be mounted on either of such opposite sides. 30

4. A pump-head, comprising a casing; a vertically reciprocable member mounted in said casing; means for reciprocating said reciprocable member; said means including a gear, a pinion meshing therewith, and a shaft on which said pinion is mounted; a bearing for said shaft adjacent said pinion; said casing being adapted to contain a supply of oil into which said reciprocable member, at the bottom of its stroke, and said gear dip; and provisions for distributing to 45 said bearing at least a portion of the oil which adheres to the teeth of said gear and which is forced axially therefrom by said pinion.

5. A pump-head, comprising a casing, a pair of vertical guide-rods, said casing being provided with sockets for receiving the lower ends of said guide rods and in its upper portion with holes which receive and locate the upper ends of said guide-rods and through which the guide-rods can be drawn upwardly to remove them 50 from the casing, a cross-head mounted on said guide rods for sliding movement, a bracket mounted within said casing, and mechanism mounted on said bracket for reciprocating said cross-head, said bracket and said mechanism being removable as a unit from said casing and from association with said cross-head. 55

6. A pump-head as set forth in claim 4 with the addition that said bearing is provided in its shaft-engaging face with a generally longitudinally extending oil groove having an inlet opening positioned adjacent the point at which said gear and pinion mesh, said bearing also having an oil reservoir with which said groove communicates. 65

7. A pump-head as set forth in claim 4 with the addition that said bearing is provided in its shaft-engaging face with a generally longitudinally extending oil groove having an inlet 70 opening positioned adjacent the point at which said gear and pinion mesh, said bearing also having an oil reservoir with which said groove communicates. 75

opening positioned adjacent the point at which said gear and pinion mesh.

8. A pump-head, comprising a casing, a cross-head mounted for vertical sliding movement in said casing, said cross-head having a transverse guide-way, a gear rotatable about an axis perpendicular to said guide-way and to the path of movement of said cross-head, a block rotatably mounted at an eccentric point on said gear and slidably received in said guide-way,

said casing being adapted to contain a supply of oil into which said gear dips, a pinion meshing with said gear at a point above the level of the oil in said casing, said gear and pinion being disposed adjacent the cross-head whereby oil adhering to the teeth of said gear and forced axially therefrom by said pinion will be delivered against the adjacent face of said cross-head and into said guide-way.

RAYMOND E. SWANSON. 10
